US00D996735S

(12) **United States Design Patent** (10) **Patent No.:** **US D996,735 S**
Chen (45) **Date of Patent:** **** Aug. 22, 2023**

(54) **INFLATABLE DOG WATER RAMP**

(71) Applicant: **Shuixian Chen**, Guangdong (CN)

(72) Inventor: **Shuixian Chen**, Guangdong (CN)

(**) Term: **15 Years**

(21) Appl. No.: **29/876,763**

(22) Filed: **May 26, 2023**

(51) LOC (14) Cl. **30-03**

(52) U.S. Cl.

USPC **D30/199**

(57) **CLAIM**

The ornamental design for an inflatable dog water ramp, as shown and described.

DESCRIPTION

FIG. 1 is a front, bottom perspective view of an inflatable dog water ramp, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the inflatable dog water ramp that form no part of the claimed design.

1 Claim, 8 Drawing Sheets
